UNITED STATES PATENT OFFICE

2,660,214

MACHINE FOR OPERATING ON METAL STOCK BY ROLLERS

Ernest Lambert Tinley, Wolverhampton, and Henry Albert Hallett, Cheltenham, England, assignors to Joshua Bigwood & Son, Limited, Wolverhampton, England, a British company

Application August 22, 1951, Serial No. 246,898

7 Claims. (Cl. 153—54)

1

This invention relates to machines for operating on metal stock by rollers, for example machines for bending metal plates, shape and section straightening machines and roller levellers, these machines being provided with means for adjusting the rollers or roller shafts in a direction transverse to their length. For instance in a plate-bending machine having a plurality of rollers it is usual to provide separate and independent vertical adjustments for each end bearing of the top roll shaft and to provide for simultaneous adjustments for the end bearings of the back roll shaft by making the respective bearing housings slidably adjustable in the machine frame.

The object of the present invention is to provide on the machine or elsewhere indicating means for showing the positions of the axes of the adjustable rolls. Furthermore, the present invention provides means whereby either on the machine or at a remote position a plurality of indicators are grouped together so that all the desired indicators can be seen at a glance.

The present invention incorporates an indicating device of known construction per se, or a number of such devices each comprising a transmitter and a receiver, each of these members having a rotor and a stator, the latter providing an electrically-generated magnetic field in which the rotor is mounted for rotation, the two rotors being formed as armatures each having a winding, and the two windings being electrically coupled to those of the receiver, and the arrangement being such that when the windings of the rotors are energised by alternating current, angular movements of the rotor of the transmitter are automatically reproduced in the rotor of the receiver. This known type of indicating device is referred to in the claims appearing herein-after as "a rotary electromagnetic data transmitter and receiver system."

According to the present invention, in a machine of the kind described the transmitters of indicating devices of the type specified are mounted on the machine frame adjacent the adjustable bearing housings of the roll shafts, and mechanical means are provided for converting linear sliding movements of each adjustable bearing housing into angular movements of a transmitter rotor, the receivers of which are coupled to these transmitters, all being mounted near each other upon the machine or at a position remote therefrom, and each receiver rotor being adapted to operate a roll position indicator.

The mechanical means for operating the rotor

of a transmitter may comprise a sprocket wheel or pulley secured on the rotor spindle, this sprocket wheel or pulley having a flexible member, such for example as a length of sprocket chain attached to its periphery by one end, the opposite end of the flexible member being connected with the roll shaft bearing housing and a spring being provided which is tensioned by rotation of the rotor spindle in one direction, whereby the flexible member is kept in a state of tension.

The invention will now be further described with reference to the accompanying drawings, in which:

Figure 1 is a front elevation partly in section of a sheet metal bending machine constructed according to the invention;

Figure 2 is a plan view partly in section of the machine shown in Figure 1;

Figure 3 is a sectional side elevation on the line 3—3 of Figure 1;

Figure 4 is a fragmentary sectional elevation on the line 4—4 of Figure 3, this view being to an enlarged scale;

Figure 5 is a side elevation of Figure 4;

Figure 6 is a sectional end elevation showing a detail of construction; and

Figure 7 is a sectional view to an enlarged scale on the line 7—7 of Figure 3.

Referring to the drawings, the machine is of generally known construction and comprises a pair of non-adjustable bottom rolls 10, a top roll 11 and a back roll 12. The shaft of the top roll 11 is mounted in end bearing housings 13 and 14, respectively, each housing being supported at the upper end of a screwthreaded shaft 15 which engages the correspondingly screwthreaded bore of a worm wheel 16. Rotation of the worm-wheels 16 raises or lowers the bearing housings 13 and 14, thus providing adjustment of the top roll 11, and these worm wheels are power driven by means of worms 17 on a shaft 18; this shaft being capable of connection with a driving shaft 19 associated with a main gearbox 20 by means of a clutch 21 having a control lever 22. A further clutch 23 is provided on the shaft 18 between the worms 17 so that the bearing housing 13 may be raised or lowered independently of the bearing housing 14.

Each shaft 15 is enclosed in a housing 24, the lower end of which is provided with a tubular extension 25, and at the bottom end of each shaft 15 is secured a coaxial rod 26 (Figures 4 and 5), and these rods perform the same raising and lowering movements as do the shafts 15 and bearing housings 13.

3

At the lower end of each tubular extension 25 is secured the transmitter 27 of an indicating device of the type previously described, and upon the rotor shaft 28 of each transmitter is secured a sprocket wheel 29. A sprocket chain 30 is anchored by one end 31 to the sprocket wheel, is passed around the periphery of the wheel 29, and is connected by its other end to the lower end of the rod 26 by a turnbuckle 32 which provides a means for adjusting the effective length of the chain 30. A spiral spring (not shown) is associated with the spindle 28 of the transmitter 27, and is tensioned as the sprocket wheel 29 is rotated in a direction to unwind the chain 30 therefrom as the rod 26 rises, so that the chain is maintained in a state of tension, and will rewind back onto the sprocket when the rod 26 moves downwardly.

A safety device to prevent overwinding of the chains 30 back into the sprockets 29 is indicated diagrammatically in Figure 6, a cam 33 being provided on the rotor shaft 28 of the transmitter, and an electric cutout or "limit" switch, indicated at 34, being provided in the path of the cam for operation thereby should the sprocket rotate to a position from which further rotation would endanger the transmitter-actuating mechanism. The switch 34 may operate in any well-known manner to stop the driving of the worm or worms 17, as for instance by cutting off current supply to the machine-driving motor 35 (Figure 2) until either the clutch 21 is disengaged, or the rotation of the driving shaft 19 is reversed through the medium of the gearbox 20.

The back roll 12 (Figures 3 and 7) is mounted in similar end bearing housings 36 which are both adjusted together identically, each being carried at the upper end of a screwthreaded rod 37 and the rods being moved up or down in like manner to the rods 15 by worms 38 and wormwheels 39 on a shaft 40, the shaft 40 being driven from the driving shaft 19 by the sprocket chain 41. A clutch 42 operated by a lever 43 is provided on the shaft 40 for connection or disconnection of the drive to the shaft 40, as desired, but both worms 38 rotate together.

One bearing housing 36 has one end of a sprocket chain 30 (Figure 7) secured to a lug 44 on the housing by means of turnbuckle 32, and the other end of the chain 30 is secured to a sprocket wheel 29 on the rotor shaft 28 of a transmitter 27, the operation thereof being as previously described with reference to the top roll.

The three transmitters 27 are coupled with three receivers (not shown), the rotor shafts of which operate pointers 45 (Figures 1 and 2) which move over suitably calibrated dials 46, and the dials will be suitably marked, so that each is identifiable with the particular roll-bearing housing movement it is recording. In the example described one dial will indicate the position of the axis of the back roll, of which both bearing housings must be adjusted together, but the other two dials will each record the movement of one of the end bearing housings of the top roll, and as one can be adjusted independently of the other to place the roll in a tilted position relative to the fixed rolls for special work, the difference between the position of the roll axis at one end bearing and at the other end bearing will be readily observable by comparing the two dials.

All the receivers are mounted near each other upon an indicator panel 47 situated near the clutch-operating levers 23, 43, and the motor and

4

gearbox operating levers 48, so that all the indicator dials can be readily observed by the machine operator, who by this invention can effect roll adjustment with speed and accuracy.

5. What we claim then is:

1. In combination with a machine for operating on metal stock by rollers of the kind having at least a pair of co-operating rollers on spaced parallel axes, at least one of which rollers is supported in bearings which are linearly adjustable for the purpose of adjusting the position of this roller in relation to the co-operating roller; a rotary electromagnetic data transmitter and receiver system including a transmitter having a rotor, a flexible driving member of elongated form, connected at one end with an adjustable bearing and connected at the other end with the rotor of the transmitter so as to produce angular movement of the rotor in response to linear movement of the bearing, means for maintaining said flexible driving member in a state of tension and a roller position indicator including a scale and a pointed co-operating therewith and operatively connected with the receiver rotor of the transmitter and receiver system.

2. In combination with a machine for operating on metal stock by rollers of the kind having at least a pair of co-operating rollers on spaced parallel axes, at least one of which rollers is

30 supported in bearings which are linearly adjustable for the purpose of adjusting the position of this roller in relation to the co-operating roller; a rotary electromagnetic data transmitter and receiver system including a transmitter having a rotor, a wheel or pulley mounted on the spindle of said transmitter rotor, a flexible driving member of elongated form, connected at one end with an adjustable bearing and connected at the other end to the periphery of said wheel or pulley so as to produce angular movement of the rotor in response to linear movement of the bearing spring means acting on said rotor spindle so as to maintain the driving member in a state of tension and a roller position indicator including a scale and a pointer co-operating therewith and operatively connected with the receiver rotor of the transmitter and receiver system.

3. In combination with a machine for operating on metal stock by rollers of the kind having

50 at least a pair of co-operating rollers on spaced parallel axes, at least one of which rollers is supported in bearings which are linearly adjustable for the purpose of adjusting the position of this roller in relation to the co-operating roller;

55 a rotary electromagnetic data transmitter and receiver system including a transmitter having a rotor, a sprocket wheel mounted on the spindle of said transmitter rotor, a driving member comprising a length of sprocket chain, connected at one end with an adjustable bearing and having the other end in driving engagement with said sprocket wheel so as to produce angular movement of the rotor in response to linear movement of the bearing, spring means acting on said rotor spindle so as to maintain the driving member in a state of tension, and a roller position indicator including a scale and a pointer co-operating therewith and operatively connected with the receiver rotor of the transmitter and receiver system.

60 4. In combination with a machine for operating on metal stock by rollers of the kind having

65 at least a pair of co-operating rollers on spaced parallel axes, at least one of which rollers is supported in bearings which are linearly adjust-

75 supported in bearings which are linearly adjust-

able for the purpose of adjusting the position of this roller in relation to the co-operating roller; a rotary electromagnetic data transmitter and receiver system including a transmitter having a rotor, a sprocket wheel mounted on the spindle of said transmitter rotor, a driving member comprising a length of sprocket chain, a turnbuckle connecting one end of said chain with an adjustable bearing, the other end of said chain being in driving engagement with said sprocket wheel so as to produce angular movement of the rotor in response to linear movement of the bearing, spring means acting on said rotor spindle so as to maintain the driving member in a state of tension, and a roller position indicator including a scale and a pointer co-operating therewith and operatively connected with the receiver rotor of the transmitter and receiver system.

5. In combination with a machine for operating on metal stock by rollers of the kind having a top roller supported in bearings which are independently adjustable in a direction at right angles to the roller axis and a back roller supported in bearings which are simultaneously adjustable in a direction at right angles to the back roller axis, a rotary electromagnetic data transmitter and receiver system including a transmitter mounted on the machine frame adjacent each bearing of the top roll and a transmitter mounted on the machine frame adjacent one of the bearings of the back roll, each transmitter having a rotor, a wheel or pulley mounted on the spindle of each transmitter rotor, a flexible driving member of elongated form, associated with each rotor, connected at one end with the associated adjustable bearing and connected at the other end to the periphery of said wheel or pulley so as to produce angular movement of the rotor in response to linear movement of the bearing, spring means acting on each rotor spindle so as to maintain each driving member in a state of tension, a receiver associated with each transmitter, all the receivers being in close association with each other and a roller position indicator for each receiver including a scale and a pointer co-operating therewith and operatively connected with the associated receiver rotor.

6. In combination with a machine for operating on metal stock by rollers of the kind having a top roller supported in bearings which are independently adjustable in a direction at right angles to the roller axis and a back roller supported in bearings which are simultaneously adjustable in a direction at right angles to the back roller axis, a rotary electromagnetic data transmitter and receiver system including a transmitter mounted on the machine frame ad-

jacent each bearing of the top roll and a transmitter mounted on the machine frame adjacent one of the bearings of the back roll, each transmitter having a rotor, a sprocket wheel mounted on a spindle of each transmitter rotor, a driving member comprising a length of sprocket chain, connected at one end with the associated adjustable bearing and having the other end in driving engagement with said sprocket wheel so as to produce angular movement of the rotor in response to linear movement of the said bearing, spring means acting on each rotor spindle so as to maintain each driving member in a state of tension, a receiver associated with each transmitter, all the receivers being in close association with each other and a roller position indicator for each receiver including a scale and a pointer co-operating therewith and operatively connected with the associated receiver rotor.

7. In combination with a machine for operating on metal stock by rollers of the kind having a top roller supported in bearings which are independently adjustable in a direction at right angles to the roller axis and a back roller supported in bearings which are simultaneously adjustable in a direction at right angles to the back roller axis, a rotary electromagnetic data transmitter and receiver system including a transmitter mounted on the machine frame adjacent each bearing of the top roll and a transmitter mounted on the machine frame adjacent one of the bearings of the back roll, each transmitter having a rotor, a sprocket wheel mounted on the spindle of each transmitter rotor, a driving member comprising a length of sprocket chain, a turnbuckle connecting one end of each said chain with its associated adjustable bearing, the other end of said chain being in driving engagement with a said sprocket wheel so as to produce angular movement of the rotor in response to linear movement of the bearing, spring means acting on each rotor spindle so as to maintain the driving members in a state of tension, a receiver associated with each transmitter, all the receivers being in close association with each other and a roller position indicator for each receiver including a scale and a pointer co-operating therewith and operatively connected with the associated receiver rotor.
